United States Patent Office.

JOHN SCHLEY, OF SAVANNAH, GEORGIA.

Letters Patent No. 66,401, dated July 2, 1867.

IMPROVEMENT IN HORSE-POWERS.

The Schedule referred to in these Letters Patent and making part of the same.

TO ALL WHOM IT MAY CONCERN:

Be it known that I, JOHN SCHLEY, of Savannah, in the county of Chatham, and State of Georgia, have invented a new and improved Horse-Power Machine; and I do hereby declare that the following is a full, clear, and exact description thereof, which will enable others skilled in the art to make and use the same, reference being had to the accompanying drawings, forming part of this specification, in which—

Figure 1 is a vertical central section of my improved horse-power machine.

Figure 2 is a plan.

Similar letters of reference indicate like parts.

This invention relates to an improvement in the construction and arrangement of a machine to be used as a horse-power, and is especially designed for plantation use, to be applied to mills and all other purposes, the nature of my invention consisting in an arrangement of machinery by which I am enabled to increase the speed of the machine conveniently and economically.

In constructing my horse-power machine I employ two cog-wheels, of equal size and about six feet diameter, one of them being double cogged; that is, having teeth both above and below, as shown at A, and the other being cogged on the under side, as shown at B, both wheels being horizontally mounted in a strong square frame, C, one at the top and the other at the bottom. The upper wheel B is stationary, and is rigidly secured to the framing of the machine, while the lower wheel A rotates loosely around and independent of a post or stud, D. These and all the wheels in the machine are bevel-gears. The lower one, A, engages in a pinion, E, on its under side, to drive the pulley F, from which the power is taken. The shaft a, on which the pinion and pulley are hung, is placed low down and covered for the horses to travel over in working the machine. Two vertical wheels G G, of the same size, are hung opposite each other upon axles b b, which are made fast to the under side of a horizontal wheel, H, which also revolves loosely around and independent of the post D. The wheel H is cogged on the upper side and gears into two vertical bevel-wheels K K, which are hung opposite each other upon the ends of an axle, L, that pivots on the upper end of the post D, and is made fast to the lower end of a short vertical shaft, M, which passes up through the upper horizontal wheel B, and has the lever or sweep N connected with its upper end. The wheels K K also gear into a concentric rim, P, placed on the under side of the wheel B. The wheels are geared for speed as two to one, but any other suitable proportion may be applied in the construction as desired. The sweep N is placed at a proper height to suit the line of draught of the horses.

It will be seen that when the sweep N is moved around the shaft M will revolve the two wheels K K on the axle L, and that they will give motion to the wheel H, which will carry around the vertical wheels G G on the axles b b, and that the wheels G G will turn the lower wheel A to move the pinion E below, and thus rotate the pulley F, from which the power is transmitted wherever it may be desired.

Having thus described the construction and operation of my invention, what I claim as new, and desire to secure by Letters Patent, is—

The arrangement of the vertical gear-wheels K upon the horizontal shaft L, secured to the vertical shaft M, and pivoted on the post D, meshing into the horizontal gear-wheel H, turning loosely upon the post D, said wheel H provided upon its under side with horizontal shafts b, upon which the vertical gear-wheels G are supported, the latter meshing into the stationary wheel B and double-cogged revolving gear-wheel A, substantially as described for the purpose specified.
